CLAIM

The ornamental design for an illuminated control device as
shown and described.

DESCRIPTION

FIG. 1 is a front perspective view of an illuminated control
device showing our new design;
FIG. 2 is a front view thereof;
FIG. 3 is a left side view thereof;
FIG. 4 is a right side view thereof;
FIG. 5 is a top view thereof;
FIG. 6 is a bottom view thereof;
FIG. 7 is a front perspective view of a second embodiment
thereof;
FIG. 8 is a front view thereof;
FIG. 9 is a left side view thereof;
FIG. 10 is a right side view thereof;
FIG. 11 is a top view thereof; and,
FIG. 12 is a bottom view thereof.

(Continued)

The drawings include shadows and reflections which indicate contour, not surface ornamentation, and form no part of the claimed design.

1 Claim, 6 Drawing Sheets

Related U.S. Application Data

continuation of application No. 29/723,770, filed on Feb. 10, 2020, now Pat. No. Des. 951,885.
